UNITED STATES PATENT OFFICE.

JOHN H. NELSON, OF CHICAGO, ILLINOIS.

VELOCIPED.

Application filed March 26, 1923. Serial No. 627,540.

To all whom it may concern:

Be it known that I, JOHN H. NELSON, a citizen of the United States, residing at Chicago, in the county of Cook and State 5 of Illinois, have invented a certain new and useful Velocipede, of which the following is a specification.

The invention relates to velocipedes and especially to tricycles; and the general object 10 of the invention is to produce a velocipede of a thoroughly practical character, rugged in construction and yet simplified so that it may be manufactured on an economical basis.

15 A special aim of the invention has been to produce a tricycle combining in a practical manner the advantages of the bicycle and tricycle types of velocipedes.

A still further object is to provide a construction 20 for the frame such that it will possess ample strength and rigidity, may be cheaply constructed, and will present a neat appearance.

Still another object of the invention is to 25 provide a tricycle which may be equipped with a second seat or carrier adapted to occupy an out-of-the-way position when not in use and serving when in this position as a bundle carrier.

30 The objects of the invention thus generally set forth, together with other and ancillary advantages, may be attained by the construction and arrangement illustrated in the accompanying drawings forming part 35 hereof wherein I have illustrated the invention in its preferred form. It is contemplated, however, that various changes may be made by those skilled in the art without departing from the spirit and scope of the 40 invention as expressed in the appended claims.

Figure 1 of the drawings is a side elevational view of a tricycle embodying my invention. Fig. 2 is an underside view of the 45 rear portion of the tricycle, partially in section to show details of construction. Fig. 3 is an underside view of the combined seat and carrier detached. Fig. 4 is a fragmentary sectional view showing a modified 50 form of the diagonal frame member. Fig. 5 is a fragmentary vertical sectional view illustrating the frame construction and the adjustable mounting of the crank shaft. Fig. 6 is a fragmentary detail view illustrating 55 the construction of the front fork.

Fig. 7 is a fragmentary elevational view showing the seat in its operative position.

The velocipede comprises a frame 8 supported upon a front wheel 9 and a pair of rear wheels 10, the latter being of any usual 60 or preferred construction. 11 indicates the saddle, which is mounted upon the frame in the usual way, and 12 the handle bars secured to the front steering fork 13.

The rear wheels 10 are mounted at the 65 opposite ends of an axle 14, one wheel (herein the right) being made rigid with the axle in any suitable way as by means of a key 15, and the left wheel being free.

The rear axle 14 is mounted in two aligned 70 tubular cross members 16 constituting elongated journal bearings for the opposite ends of the axle and also serving as firm non-rotatable foot supports. A pair of upright members 17 are rigidly secured to the adjacent ends of the cross members 16 and extend slightly forwardly and inwardly, forming a triangle with the cross members. The latter are connected with an upright front frame member 18 by a diagonal member 75 19 extending in an upwardly and forward direction. Between the front frame member 18 and the upright rear members 17 extends a top bar 20; and from the juncture of the bar 20 and the member 17 a downwardly and forwardly extending frame member 21 proceeds for connection at its lower end with the midportion of the frame member 19.

The frame is preferably made from tubular stock, the separate portions being secured 80 together as by welding. In the case of the member 19, two pieces of stock are employed. Thus the rear end portion 19^a is made from one piece bent into U-form (Fig. 2) and 85 rigidly secured at its bight end with the forward end portion 19^b which may be made from a straight piece of stock. The lower ends of the U-portion 19^a are welded to the adjacent ends of the members 16 and the 100 arms of the U-portion are secured together by a cross piece 19^c. The members 16 are thus rigidly connected together but in such a manner as to form a space between them to receive a portion of the propelling means 105 as hereinafter set forth.

In Fig. 4 I have shown the frame member 19 as formed from two solid rods bent into U-form as indicated at 22 and 23 and welded 110 together at their bight-ends with the frame

member 21. The free ends of these U-ports 22 and 23 are respectively welded to the front member 18 and to the rear cross members 16. This latter form, as illustrated 5 in said Fig. 4, possesses the advantage that it may be more cheaply constructed.

Tricycles now in general use employ as the actuating means pedal-carrying cranks rigid with the front steering wheel. This 10 method of propulsion is objectionable in that when the wheel is turned, and especially when turned rather sharply, the child's leg upon the far side of the wheel must be stretched or extended into an uncomfortable position and frequently comes in contact with the wheel. I have overcome this objection by providing a propelling means generally similar to that commonly employed in bicycles. Thus I provide in 15 the present instance a chain and sprocket mechanism including a front or large sprocket 24 fast upon a crank shaft 25 which is journalled in bearings 26 at the lower ends of a U-shaped member or fork 20 27 supported by the frame 8. Upon the rear axle 14 a small sprocket 28 is rigidly secured. This sprocket is located between the rear frame members 16 and the arms of the rear end of the diagonal frame member 25 27 30 19, sufficient space only being provided between the members 16 to receive the sprocket 28. A chain 29 of usual or preferred construction connects these sprockets; and crank arms 30 are rigid with the 35 opposite ends of the shaft 25 and carry pedals 31.

By making the frame member 19 and the support 27 for the sprocket 24 in bifurcated or U-form, it is possible to locate the chain 40 and sprockets in medial position. An important advantage in this is that it avoids the necessity of using especial bearings as is usual in bicycle construction where the chain and sprocket mechanism is located to 45 one side of the frame.

The sprocket fork 27 is also preferably made from tubular stock, and at the lower ends of the fork arms I weld or otherwise secure elongated tubular members forming 50 the bearings 26 for the crank shaft. The fork has at its upper end a shank 33 rigidly secured thereto as by welding, and this shank extends upwardly into the frame through the member 19 and into the member 21 (Fig. 5). The shank is by preference secured in position by means of a set screw 34, which provides for adjustment to accommodate children of varying sizes, this adjustment being in addition to that which 55 is provided in the mounting of the saddle 11. By reason of the forward and downward inclination of the frame member 21, it will be apparent that when the fork 27 is adjusted downwardly, it will also move 60 forwardly. This will serve to take up any

slack in the chain which naturally follows the wear which occurs during the growth of the child which necessitates the downward adjustment. However, the chain 29 preferably is of that type which embodies 70 links which may be detached or inserted at will.

The front fork member 13 is especially constructed to reduce its cost of manufacture. Thus it may be made from solid stock (Figs. 1 and 6) bent up from a single rod to form front and rear U-members 35 and 36 integrally connected at their lower ends and shaped at this point to form eye members 37 for receiving a short shaft 75 or axle 38 upon which the front steering wheel 9 is journalled. At their upper ends the U-members 35 and 36 are welded to a head member 39 which carries an upwardly projecting stem or shank 40 journalled in the front frame member 18. The extreme upper end of the member 40 is connected to the shank 41 of the handle bars 12 by suitable means including a clamping collar 42.

The rear seat or luggage carrier is adapted to be detachably supported upon the upright rear frame members 17, and preferably it comprises a pair of side bars 43 connected at one end by a cross bar 44 and having at their opposite ends downturned portions 45 which are adapted to enter socket members 46 rigidly secured upon the rear sides of the frame members 17 as by welding. A seat member 47 is made of leather or the like and extends around the side frame members 43, their adjoining ends being laced together as at 48. Preferably the rear edge of the seat is wrapped around the cross bar 44 and stitched to the seat proper as at 49. The opposite or forward edge of the seat is left open. When the seat is in use, the downturned portions 45 are entered in the socket members 46, with the seat extending rearwardly as shown in Fig. 7; and the proportioning of the parts is such that while the seat is located rearwardly of the rear axle, the weight forwardly of the axle, especially when occupied by a child seated upon the saddle 11, is ample to prevent any rearward tilting of the device. When the rear seat is not in use the rear ends 43a of the side bars 43 may be entered in the socket members 46 as shown in Fig. 1. In this relation of the parts the seat is in an out-of-the-way position, and at the same time the seat portion proper, being open at its upper end, constitutes a receptacle for receiving books, packages, or the like.

As shown in broken lines in Fig. 1 the chain and sprocket mechanism is in practice preferably enclosed within a housing of any suitable or preferred character. 125 It will be observed that I have produced a tricycle which is capable of manufacture at 130

a relatively low cost and yet one which presents numerous advantages over the tricycle now in common use. By the provision of the chain and sprocket drive, the device 5 embodies the advantage of the bicycle residing in the facility with which it may be steered and operated, and the use of two rear wheels instead of one, as is the case in the bicycle, renders it possible for use by 10 children without danger of tipping. The frame construction lends strength and rigidity to the device as a whole, and also provides an advantageous mounting for the driving means without resort to expensive 15 equipment.

I claim as my invention:

1. A tricycle having, in combination, a frame having front and rear supporting wheels, and propelling means independent 20 of the front wheel and operatively connected with one of the rear supporting wheels, said propelling means including a crank shaft, and said frame including a tubular upwardly and rearwardly extending member open 25 at its lower end, a fork having a shank secured in the lower end of said frame member and having journal bearings in its lower free ends in which said shaft is mounted, and 30 pedal-carrying crank arms fast upon said shaft.

2. A tricycle comprising a frame having two alined elongated cross members in its lower rear portion, a rear wheel supporting axle journaled in said cross members, and 35 propelling means including a gear element fast upon said axle midway between its ends, said cross members being spaced apart to receive said gear element, and said frame also including a pair of members extending 40 upwardly and forwardly from each of the rear cross members upon opposite sides of said gear element, said pair of members being connected together near their lower ends whereby to connect the rear cross members. 45

3. A tricycle comprising a frame having alined cross members and an uprightly disposed front member, a front steering wheel having a fork journaled in the front frame member, a pair of rear supporting wheels 50 having an axle journaled in the rear cross members, said frame also including a member extending downwardly and rearwardly from the front frame member to the rear cross members, and an intermediate uprightly disposed member extending upwardly 55 from said downwardly and rearwardly inclined frame member, and propelling means including a gear element having a supporting fork adjustably secured within said up- 60 right intermediate frame member.

4. A tricycle comprising a frame having alined rear cross members and an uprightly disposed front member, a front steering wheel having a fork journaled in the front 65 frame member, a pair of rear supporting

wheels having an axle journaled in the rear cross members, said frame also including a member extending downwardly and rearwardly from the front frame member to the rear cross members, and propelling means 70 including a main operating gear element having a supporting fork depending from said downwardly and rearwardly inclined frame member substantially midway between the front and rear supporting wheels. 75

5. A tricycle comprising a frame having alined rear cross members, a pair of uprightly disposed rear frame members rigidly connected with the respective cross members and extending inwardly so as to form 80 a triangle with said cross members, and propelling means including a rear wheel supporting axle journaled in said cross members and having a gear element rigidly secured thereto midway between its ends, said 85 cross members being spaced apart to receive the gear element.

6. A tricycle comprising a frame having a diagonal frame member extending downwardly and rearwardly in the frame, and an uprightly disposed member extending upwardly and rearwardly from said diagonal frame member from a point approximately midway between the ends of the latter, said diagonal member having a bifurcated rear 90 or lower end portion formed from a piece of metal bent into U-form and rigidly secured to the forward portion of said diagonal frame member and to the lower end 95 of said upright frame member. 100

7. A tricycle comprising a frame having a diagonal frame member extending downwardly and rearwardly in the frame, and an uprightly disposed member extending upwardly and rearwardly from said diagonal frame member from a point approximately midway between the ends of the latter, said diagonal member having a bifurcated rear 105 or lower end portion formed from a piece of metal bent into U-form and rigidly secured as by welding to the forward portion of said diagonal frame member and to the lower end of said upright frame member, and propelling means for the tricycle including 110 a rear wheel supporting axle, a crank shaft having its support at the juncture of said upright frame member with the diagonal frame member, sprockets on said shaft and rear axle respectively, and a chain extending over said sprockets and passing between the 115 arms of the bifurcated rear end of the diagonal member. 120

8. A tricycle having a frame including a diagonal member extending in a downward and rearward direction, a pair of alined rear cross members, the lower rear end of the diagonal member being bifurcated and integrally connected with said cross members, the latter being spaced a short distance apart, and propelling means including a 125 130

rear wheel supporting axle journalled in the cross members and having a gear element thereon between the cross members, a second gear element having a crank shaft, a fork 5 rigidly secured to and depending from said diagonal frame member and having said crank shaft journalled in its lower free ends, a chain passing over said gear element and between the arms of the diagonal frame 10 member and said supporting fork, and means for operating said crank shaft.

9. A velocipede having a frame including a downwardly and rearwardly extending diagonal member constructed from two pieces 15 of solid rod stock each bent into U-form and having its bight end welded to the bight end of the other, the lower rear end of the frame member constituting a fork to receive between its arms the chain of the propelling 20 means.

10. A velocipede having a rear supporting wheel and a frame in which said supporting wheel is mounted having a pair of elongated alined cross-members, a rear axle having one of said supporting wheels rigid therewith 25 and journalled in said cross members, and propelling means including a gear element fast upon said axle, said frame including a diagonal frame member constructed from two separate pieces of stock one of which is bent into U-form and integrally secured to the other to form spaced arms the ends of which are integrally secured to said cross members, the latter being spaced apart between said arms to receive the gear element 30 35 on the rear axle.

In testimony whereof, I have hereunto affixed my signature.

JOHN H. NELSON.
